[57] CLAIM

The ornamental design for a pipe supporting and spacing member, as shown and described.

DESCRIPTION

FIG. 1 is a top plan view of a pipe supporting and spacing member showing my new design;

FIG. 2 is a front view thereof;

FIG. 3 is a bottom plan view thereof;

FIG. 4 is a right side end view thereof;

FIG. 5 is a fragmentary perspective view thereof, with the showing in broken lines being for illustrative purposes only.
